UNITED STATES PATENT OFFICE.

ABRAHAM ELKINS AND MYER PERSTEN, OF BROOKLYN, NEW YORK.

BED-CORNER.

1,119,690.

Specification of Letters Patent.

Patented Dec. 1, 1914.

Application filed January 14, 1914. Serial No. 812,071.

To all whom it may concern:

Be it known that we, ABRAHAM ELKINS and MYER PERSTEN, subjects of the Czar of Russia, residing at Brooklyn, in the county 5 of Kings and State of New York, have invented new and useful Improvements in Bed-Corners, of which the following is a specification.

The general object of the invention is to 10 refine the construction of bed frames, whereby the side rails may be arranged to accommodate either the usual form of flat bed spring or the usual form of box bed spring as now used in bed construction. And to 15 this end the invention consists of a bracket adapted to be connected to the upright of the bed and a side rail formed of angle iron adapted to interlock with the bracket, the side rail when arranged in one position 20 adapted to accommodate a flat bed spring and when arranged in another position adapted to accommodate a box bed spring.

Other objects will appear and be better understood from that embodiment of our invention of which the following is a specification, reference being had to the accompanying drawings forming part hereof, in which:

Figure 1 is a perspective view of a portion of a bed frame with the invention applied thereto. Fig. 2 is an enlarged detail cross sectional view of one of the bed uprights with its connecting parts shown in plan. Fig. 3 is a detail perspective view of 35 one of the attaching brackets. Fig. 4 is a detail perspective view of an end of one of the side rails.

Referring to the drawings in detail 1 indicates one of the uprights of a bed frame 40 to which is detachably connected by means of a rod 2, a bracket 3 for supporting the side rail 4. These various parts are formed of the usual metal employed in the manufacture of the standard makes of beds and 45 the brackets are so designed and constructed that they may be connected to the uprights at either end of the bed frame, if desired.

The bracket is preferably formed of a single piece of metal of the shape shown 50 and comprises a central web portion 5 having one of its ends provided with a curved strengthening rib 6 for embracing the outer side of the tubular upright, as shown. A

staple or keeper 7 is horizontally arranged on one side of the rib 6 and is provided for 55 the purpose of forming one element of an interlocking means by which the bracket may be securely held to the tubular upright. A slotted opening 8 is provided in the upright (see Fig. 2) and through this opening 60 the staple is inserted. When the staple is arranged within the upright the rod 2 which forms the other element of the interlocking means, is passed through the opening of the staple whereby the locking of the 65 bracket to the upright is effected in a rigid and secure manner. The rod may be held in the upright in any desired manner, and its upper end may be secured to the knob arranged on the upper end of the upright 70 so that the rod can be conveniently manipulated when desired. 10 and 11 indicate laterally extending keepers arranged on the other end of the web portion 5 at right angles thereto. These keepers are each provided with vertically arranged slotted openings 12 and 13 open at their upper ends to receive the locking studs 14 and 15 mounted on the end piece 16 of side rail. These studs 75 form the means for interlocking the side 80 rail to the bracket as shown. A vertically arranged strengthening rib 18 is also provided on that portion of the brackets which interlocks with the side rail and this rib fits within a correspondingly shaped groove 85 19 formed in the end of the side rail, for the purpose of preventing any lateral movement of the side rail when interlocked with the bracket, as shown. To connect the cross rail to the bracket when such is used, a laterally extending plate 20 is also formed on 90 the inner side of the bracket, as shown. This plate is provided with perforations 21 through which bolts may be inserted when the side rail is connected thereto. 95

The side rail is of the usual angle iron structure and when arranged on the bracket in one position forms an open ended pocket adapted to accommodate the form of box bed spring as is now sometimes used. When 100 the side rail is desired to be arranged to accommodate the usual form of flat bed spring, it is unlocked from the supporting bracket and turned 180 degrees, whereupon the locking studs will again engage within 105 the keepers on the bracket and the parts will

2
be secured in the position to accommodate the flat bed spring, as above referred to.

What is claimed as new is:

Means for connecting a bed rail with an upright comprising in combination with a rail provided at its end with spaced studs and a groove, a bracket adapted to be connected with the upright and having keepers adapted to receive the studs and provided

with a rib adapted to enter the groove in 10 the rail.

In testimony whereof we affix our signatures in presence of two witnesses.

ABRAHAM ELKINS.
MYER PERSTEN.
